TRAY FOR MEDICAL EQUIPMENT

Kenneth Raines, Bethlehem, Pa., assignor to Burron
Medical Products, Inc., Bethlehem, Pa.

Filed Apr. 29, 1970, Ser. No. 22,696

Term of patent 14 years

Int. Cl. D24—02

U.S. Cl. D83—1

FIG. 1.

FIG. 2.

FIG. 3.

FIG. 4.

FIG. 1 is a top plan view of my tray for medical equipment, showing my new design;

FIG. 2 is a perspective view of my tray;

FIG. 3 is a sectional view taken on line 3—3 of FIG. 1; and

FIG. 4 is a sectional view taken on line 4—4 of FIG. 1.

I claim:

An ornamental design for a tray for medical equipment, as shown.
